INTERCOMMUNICATING SYSTEM

Richard T. Fitzpatrick, Detroit, Mich., assignor to
Wilbert I. Rudolph, Detroit, Mich.

Application February 14, 1940, Serial No. 318,874

12 Claims. (Cl. 179—40)

My invention relates to a new and useful improvement in an Intercommunicating System embodying a plurality of sound units each of which may selectively be used either as a dynamic speaker or as a transmitter, these sound units being positioned at spaced locations which may be termed stations. At each station there is provided a selector mechanism whereby the sound unit of that station may be brought into cooperative relation with the sound unit of any desired unit in the installation. At each station there is also provided a control switch, the operation of which serves to selectively alternate the sound units which have been brought into cooperative relation into either transmitters or speakers. In intercommunication systems the common method of installation is the mounting of a number of sound units at separate stations with a control at one of the stations which is termed a master station. In such installations the control of the system resides in any one station and the alternating of the sound units from speaking connection to listening connection, and vice versa, may be effected only from the master station.

It is an object of the present invention to provide an intercommunicating system in which controls will be located at each of the stations so that a person at any one of the stations may, by proper manipulation of the controls, connect to any of the other stations in the unit and alternate the sound unit so connected to serve either as dynamic speakers or as transmitters.

In intercommunicating systems where it is desired to provide complete intercommunication between the various stations as outlined above, it is quite common to use an amplifier for each station and in such installations it is generally customary to run the input and output wires up to the master stations where they are switched at that point. Even where a single amplifier is used and a single control station is used, the input and output wires are run up to the master station and switched at that point. It is an object of the present invention to provide an intercommunication system having a single amplifier and so arranged and constructed as to eliminate the necessity of running input and output wires up to the master stations.

It is another object of the invention in an intercommunication system of this type for eliminating the parasitic oscillation arising from the proximity of the input and the output wires.

It is another object of the invention to provide in an intercommunicating system a means

whereby the stations may be selectively alternated from the listening to the talking position, thereby changing the selected speaker from the input to the output of the amplifier and oppositely effecting the speaker at the master station used, that is changed over from dynamic speakers to transmitters, at a distant point through the operation, at the station, of the necessary controls for operating a relay or magnetically controlled switch at a distant point.

It is another object of the invention to provide a construction in which there is no interruption at the individual speakers resulting from the shifting from the listening position to the talk position, or vice versa.

Another object of the invention is the provision in an intercommunicating system of this type of a construction whereby the output is grounded out in the interval between the change-over so that the change-over from listening to the talk position, and vice versa, of two interconnected stations is actually made when the output is grounded out so as to remove capacity in the line and extraneous noises in the speakers.

Another object of the invention is the provision of a novel system of wiring and controls in an installation of this type whereby the various advantages referred to may be obtained and the various disadvantages commonly found in intercommunicating systems avoided.

Another object of the invention is the provision of an intercommunicating system of this type so arranged and constructed that it may be compact, highly efficient in use, easily and quickly installed, and economically manufactured and installed.

Other objects will appear hereinafter.

It is recognized that various changes and modifications may be made in the specific details of structure illustrated without departing from the spirit of the invention and it is desired that such variations and modifications shall be embraced within the scope of this invention.

Forming a part of this specification is a drawing which is a diagrammatic view illustrating the installation.

At each of the stations there is a talk-listen switch and a selector switch as well as a sound unit which may be used either as a dynamic speaker or a transmitter. In this system there is also used an amplifier 44 having the common wire 45 and provided with the output wire 46 and the input wire 47. The sound units may be termed speakers.

Each of these speakers 9, 10 and 11, in the

three-station installation illustrated, is connected on one side to the common wire 45. The speaker 9 at station No. 1 is connected to the common wire 45 by means of the wire 46 and the wire 47. One side of the speaker 10 at station No. 2 is connected to the common wire 45 by the wire 48. One side of the speaker 11 at station No. 3 is connected to the common wire 45 by the wire 49.

The other side of the speaker 9 at station No. 1 is connected by the wire 50, at the relay or solenoid mechanism A, to the switch blade 51 and to the switch blade 52 at the relay or solenoid mechanism A'. The other side of the speaking unit 10 at station No. 2 is connected by the wire 53 to the switch blade 54 at the relay or solenoid mechanism B and to the switch blade 55 at the solenoid mechanism or relay B'. The opposite side of the speaker 11 is connected by the wire 56 to the switch blade 57 of the relay or electric magnetic mechanism C and to the switch blade 58 of the relay or electric magnetic mechanism C'. The blade 51', the blade 54' and the blade 57' are connected by the wire 59 to the flexible contact 60.

At each of the relay mechanisms there is provided a hinged plate 61 which is normally swung outwardly as shown in the drawing. Each of these plates carries a rocker arm 62 so arranged and constructed that when the plate 61 is swung inwardly, this rocker arm 62 will swing upwardly and force the lower switch blade against the upper switch blade. For instance, at the relay A, the plate 61 overlies the core 63 of the electromagnet and when the coil is energized the plate 61 will swing upwardly to bring the switch blades 51' and 51 into engagement to make a circuit. The same method of operation takes place at all of the other relays illustrated and described. The lower blades 52' and 55' and 58' at the relays A', B' and C' are connected by the wire 64 to the blades 65 and 66.

The input wire 47 is connected to stationary flexible contact blades 67 and 68. The output wire 46 is connected to the stationary flexible contacts 69 and a flexible contact blade 70. A flexible contact blade 71 is grounded through the wire 72 to which also connects the common wire 45. These flexible blades 66, 71, 69, 70 and 65 are connected at one of their ends to a slidible block of insulation 73 which is slidable in one direction by a rocker arm 74 and in the other direction by a rocker arm 75, the rocker arm 74 projecting outwardly from a swingable plate 76 associated with the solenoid or relay L and the rocker arm 75 projecting outwardly from the swingable plate 77 associated with the solenoid or relay T.

The construction is such that when the coil of the solenoid L is energized, the plate 76 will be drawn inwardly so as to rock the arm 74 downwardly and slide the bar 73 downwardly. When the coil of the solenoid T is energized, the plate 77 will be swung inwardly to rock the arm 75 to force the member 73 upwardly. The contacts 78 and 79 are connected together by the wire 80. A battery 81 or other suitable source of electrical energy is provided and one side of this battery is connected by the wire 82 to one side of the coil or solenoid L and also by the wire 82 and the wire 83 to one side of the coil of the solenoid T. This wire 82 also serves to connect the same side of the battery to one side of each of the coils A, A', B, B', C, and C'. The opposite side of the battery is connected by the wire 84 to the common wire 45.

At each of the stations the control switch embodies rotatable contact arms 15, 16 and 17 which rotate in unison when manually operated. Contacts 13 and 14 are provided at each switch, the contact 14 being the "listen" contact and the contact 13 being the "talk" contact. The common wire 45 is connected by the wire 24 to an arcuate metallic plate 23 and the arm 15 is adapted to ride on the plate 23 in contact therewith so that when the arm 15 is brought into engagement with the listen contact 14, this listen contact 14 is thereby connected to the common wire 45. Similarly, when the arm 15 is rotated to engage the contact 13, this contact is connected through the wiring illustrated to the common. When the arm 15 engages the contact 14, the relay L is energized, the common being connected to the wire 83 since this wire 83 is connected through suitable wiring to the contact 14 at each of the stations.

For each of the stations there is provided a pair of electric magnetic switches or relays A and A' corresponding to station No. 1, B and B' corresponding to station No. 2, and C and C' corresponding to station No. 3.

When the arm 15 at any of the stations is moved to engage the contact 14 or the contact 13, the relay A', B', C', depending upon which station is being operated, will be energized so that these relays may be termed the station relays in that through these relays the operator is able to be on the output, which is the listening position of the station being operated, when contact 14 is engaged and vice versa when contact 13 is engaged.

The selector switch, which is positioned at each of the stations, is provided with a metallic ring 38 which is connected by the wire 27 to the common. In the drawing I have illustrated at each of the stations, contacts 1, 2 and 3 which may be engaged by the rotating arm 28 which rides over the metallic ring 38 and serves to establish electrical connection between the contact 1, 2 or 3 whichever has been engaged with the metallic ring 38. It will be noted that at the station No. 1 the contact 1, at station No. 2 the contact 2, and at station No. 3 the contact 3 is not connected by any wiring as this contact corresponds to the station at which the switch is located.

In operation, when the arm 15 is in engagement with either the contacts 14 or 13 and the arm 28 is in engagement with a selector contact 1, 2 or 3, corresponding to a different station, the coil A, B or C corresponding to the station selected will be energized and, thus, the speaker at the station selected will be electrically connected through the switch at the coil A, B or C which has been energized and the wire 91 to the contact 60. When the coil L is energized, that is when the operator at the controlling station desires to listen, the contact 60 will be electrically connected through engagement with the contact 68 to the input of the amplifier permitting the person at the selected station to talk through the speaker at that station.

When the coil T is energized, that is when the person at the operation station desires to talk, the contact 60 will be electrically connected through engagement with the contact 69 with the output of the amplifier. At the same time, the speaker at the operating station will be connected through the coil A', B' or C', as the case may be, with the contact 65 or the contact 66. When the coil L is energized, that is, when the person at the operating station desires to listen,

the contact 65 would be connected through engagement with the contact 165 with the output of the amplifier. When the coil T is energized, that is, when the person at the operating station desires to talk, a contact 65 would be moved away from the contact 165 and the contact 66 would be brought into engagement with the contact 67, thereby connecting the speaker at the operating station with the input of the amplifier.

It will be noted that in passing from the output to the input, the output is always grounded out and remains grounded out until contact with the input has been made.

The coils A', B' and C' are energized by the closing of the talk-listen switch at their own station. The coils A, B and C are energized through the closing of their corresponding switch in the selector mechanism of a station other than the station to which they relate. Thus, when the talk-listen switch at station No. 1 is moved to engage either the contacts 13 or 14, the coil A' is energized and remains energized even during the time the arm 15 is being moved from engagement with contact 13 or 14 into engagement with the other contact. The coil A is energized when the arm 28, at some station other than station No. 1, is moved to engage the contact 1 at that station, provided the talk-listen switch has been brought into engagement with either the contact 13 or 14.

In the operation of the mechanism the selector arm 28 would be moved to engage the contact corresponding to the station selected. For instance, in the drawing illustrated, the arm 28 at station No. 3 has been moved to engage contact 1 corresponding to station No. 1. When the talk-listen switch is then moved to engage either the contact 14 or 13, the coil C' would be energized as would, likewise, the coil A and these coils would remain energized so long as the talk-listen switch was engaging either contact 13 or 14, or moving from engagement with one into engagement with the other. When in engagement with contact 14, the coil L would be engaged and when the arm 15 would be moved into engagement with the contact 13, the coil T would be energized.

Thus, I have provided a simple and compact structure whereby the operator at any one of the stations has control of the system and may connect himself to any other station in the system and either talk from his station or listen, as he desires. Under such conditions the talk-listen switch at the station selected would not be manipulated, nor would the selector at the station selected be manipulated. By grounding out in the manner indicated, all of the disadvantages referred to in regard to building up capacity would be avoided and a simple and effective structure for the purposes intended is thus provided.

What I claim as new is:

1. In a communication system of the class described, a plurality of speaking units located at separated points; a selector switch for each of said units operable for establishing electrical connection between said unit and any of said other units, individually, selectively; a relay switch for each of said units, the relay switch of the selected unit being energized upon operation of a selector switch for selecting the unit; a talk-listen switch for each of said units movable to closed position, talking position and listening position, the circuit to said relay switches being energized upon movement of said talk-listen

switch to either of said positions; a second relay for each of said units, the relay for each of said units being energized upon movement of the talk-listen switch of said unit to either of said positions; and means for maintaining said first-named relay energized upon movement of the talk-listen switch from any of said positions to the other.

2. In a communication system of the class described, a plurality of speaking units located at separated points; a selector switch for each of said units operable for establishing electrical connection between said unit and any of said other units, individually, selectively; a relay switch for each of said units, the relay switch of the selected unit being energized upon operation of a selector switch for selecting the unit; a talk-listen switch for each of said units movable to closed position, talking position and listening position, the circuit to said relay switches being energized upon movement of said talk-listen switch to either of said positions; a second relay for each of said units, the relay for each of said units being energized upon movement of the talk-listen switch from any of said positions to the other; an amplifier having an input and an output; and means for connecting the output to the speaking unit at which the talk-listen switch is operated to the listen position and, simultaneously, connecting the speaking unit selected to the input.

3. In a communication system of the class described, a plurality of speaking units located at separated points; a selector switch for each of said units operable for establishing electrical connection between said unit and any of said other units, individually, selectively; a relay switch for each of said units, the relay switch of the selected unit being energized upon operation of a selector switch for selecting the unit; a talk-listen switch for each of said units movable to closed position, talking position and listening position, the circuit to said relay switches being energized upon movement of said talk-listen switch to either of said positions; a second relay for each of said units, the relay for each of said units being energized upon movement of the talk-listen switch of said unit to either of said positions; means for maintaining said first-named relay energized upon movement of the talk-listen switch from any of said positions to the other; an amplifier having an input and an output; means for connecting the output to the speaking unit at which the talk-listen switch is operated to the listen position and, simultaneously, connecting the speaking unit selected to the input, and vice versa upon movement of the operated talk-listen switch to the talking position from the listening position.

4. In a communication system of the class described, a plurality of speaking units located at separated points; a selector switch for each of said units operable for establishing electrical connection between said unit and any of said other units, individually, selectively; a relay switch for each of said units, the relay switch of the selected unit being energized upon operation of a selector switch for selecting the unit; a talk-listen switch for each of said units movable to closed position, talking position and listening position, the circuit to said relay switches being energized upon movement of said talk-listen

listen switch to either of said positions; a second relay for each of said units, the relay for each of said units being energized upon movement of the talk-listen switch of said units to either of said positions; means for maintaining said first-named relay energized upon movement of the talk-listen switch from any of said positions to the other; an amplifier having an input and an output; means for connecting the output to the speaking unit at which the talk-listen switch is operated to the listen position and, simultaneously, connecting the speaking unit selected to the input, and vice versa upon movement of the operated talk-listen switch to the talking position from the listening position; and means for grounding out the output in passing from output connection to input connection and maintaining such grounding out until the input is connected.

5. In a communication system of the class described, a plurality of speaking units positioned at spaced locations; a selector switch for each of said units for selectively connecting said unit to another of said units selected; a talk-listen switch at each of said units movable to closed position, talk position, and listen position; an amplifier having an input and an output; and a plurality of relays operable upon movement of said talk-listen switch to talk position for connecting the unit at which the switch operated is located to the input of the amplifier and the selected speaking unit to the output of the amplifier.

6. In a communication system of the class described, a plurality of speaking units positioned at spaced locations; a selector switch for each of said units for selectively connecting said unit to another of said units selected; a talk-listen switch at each of said units movable to closed position, talk position and listen position; an amplifier having an input and an output; and a plurality of relays operable upon movement of said talk-listen switch to talk position for connecting the unit at which the switch operated is located to the input of the amplifier and the selected speaking unit to the output of the amplifier, and vice versa upon movement of the operated switch to listen position.

7. In a communication system of the class described, a plurality of speaking units positioned at spaced locations; a selector switch for each of said units for selectively connecting said unit to another of said units selected; a talk-listen switch at each of said units movable to closed position, talk position and listen position; an amplifier having an input and an output; and a plurality of relays operable upon movement of said talk-listen switch to talk position for connecting the unit at which the switch operated is located to the input of the amplifier and the selected speaking unit to the output of the amplifier, and vice versa upon movement of the operated switch to listen position; and means for grounding out the output in passing from output to input.

8. In a communication system of the class described, a plurality of speaking units positioned at spaced locations; a selector switch for each of said units for selectively connecting said unit to another of said units selected; a talk-listen switch at each of said units movable to closed position, talk position and listen position; an amplifier having an input and an output; a plurality of relays operable upon movement of said

10 talk-listen switch to talk position for connecting the unit at which the switch operated is located to the input of the amplifier and the selected speaking unit to the output of the amplifier, and vice versa upon movement of the operated switch to listen position; and means for grounding out the output in passing from output to input, and maintaining such grounding out until the input is connected to the speaking unit previously connected to the output.

9. In a communication system of the class described a plurality of dynamic speaking units positioned at spaced locations; a selector switch for each of said units for selectively establishing connection between said unit and another selected unit; a talk-listen switch for each of said units movable to closed position, to talk position and to listen position; electric circuits connecting said units; a relay switch for each of said units energized upon the movement of the talk-listen switch of the unit corresponding thereto to closed, talk or listen position; a relay switch interposed in the circuit for each of said units energized upon the movement of a selector switch at any unit to position for selecting the unit corresponding to said relay switch; an amplifier having an input and an output; a pair of relays, said relays being operable for establishing communication of a speaking unit at which the talk-listen switch is operated to talk or listen position, respectively, to the input or output of said amplifier and, simultaneously, reversely connecting the speaking unit of the selected unit to the output or input of the amplifier.

10. In a communication system of the class described, a plurality of dynamic speaking units positioned at spaced apart locations; means at each of said units for selectively connecting one of said units in communication with another of said units; an amplifier having an input and an output; a talk-listen switch at each of said units having a talk position and a listen position; means for connecting said amplifier to said units; a relay switch operable upon movement of a switch at one of said units to talk position and connecting the input of said amplifier with said unit and the output of said amplifier with another unit.

11. In a communication system of the class described, a plurality of dynamic speaking units positioned at spaced apart locations; means at each of said units for selectively connecting one of said units in communication with another of said units; an amplifier having an input and an output; a talk-listen switch at each of said units having a talk position and a listen position; means for connecting said amplifier to said units; a relay switch operable upon movement of a switch at one of said units to talk position and connecting the input of said amplifier with said unit and the output of said amplifier with another unit; and means operable upon the movement of said talk-listen switch to listen position for connecting said unit to the output of said amplifier and, simultaneously connecting another unit to the input of said amplifier.

12. In a communication system of the class described, a plurality of dynamic speaking units positioned at spaced apart locations; means at each of said units for selectively connecting one of said units in communication with another of said units; an amplifier having an input and an output; a talk-listen switch at each of said units having a talk position and a listen position; means

for connecting said amplifier to said units; a relay switch operable upon movement of a switch at one of said units to talk position and connecting the input of said amplifier with said unit and the output of said amplifier with another unit; means operable upon the movement of said talk-listen switch to listen position for connecting said unit to the output of said amplifier and, simultane-

ously, connecting another unit to the input of said amplifier; and means operable upon the movement of said switch from listen position to talk position for grounding out the output of said amplifier.

5 RICHARD T. FITZPATRICK.
